UNITED STATES PATENT OFFICE.

JOHN R. REYNOLDS, OF HARTFORD, CONNECTICUT, ASSIGNOR TO THE SMYTH MANUFACTURING COMPANY, OF SAME PLACE.

SIGNATURE-HOLDING ARM OF BOOK-SEWING MACHINES.

SPECIFICATION forming part of Letters Patent No. 366,793, dated July 19, 1887.

Application filed June 17, 1886. Serial No. 205,496. (No model.)

To all whom it may concern:

Be it known that I, JOHN R. REYNOLDS, of Hartford, in the county of Hartford and State of Connecticut, have invented an Improvement 5 in Book-Sewing Machines, of which the following is a specification.

Letters Patent have heretofore been granted for book-sewing machinery in which the signature is laid upon an arm that projects from a vertical shaft, and the signature is presented to the sewing mechanism as the shaft is rotated progressively, and reference is hereby made to Letters Patent No. 220,312 for the general character of the machine in which the 15 present improvements are available.

Where the semicircular needles are made use of, as in the aforesaid patent, or such as are shown in Letters Patent Nos. 250,991 or 262,325, it is difficult to puncture the paper of the signature by the needles themselves, because such 20 needles are liable to spring or bend; hence it has usually been necessary to saw or otherwise notch the folded back edges of the signatures previous to placing the same in the machine.

The present invention relates to an improvement 25 in the arms that receive and hold the folded signatures, whereby each folded signature is punctured at the required places immediately before the needles pass into the signatures in sewing the same. Thereby the difficulty heretofore experienced of injuring the sheets by the notches is prevented, and at the 30 same time the perforations are always made at the proper places for the needles to enter, and it is only necessary to place the folded signatures properly upon successive arms as they are carried around by the revolving shaft, and in addition to this the perforations do not require to be as large as the notches heretofore 35 made use of, and they are not objectionable in appearance.

In the drawings, Figure 1 is an elevation of one of the arms and of part of the shaft for supporting the same. Fig. 2 is an end view 45 of the said arm in larger size. Fig. 3 is an elevation, and Fig. 4 a plan view, of the arm alone. Fig. 5 is an elevation, and Fig. 6 a plan view, of the connecting-bar. Fig. 7 is an elevation, and Fig. 8 a plan view, of the reciprocating bar. Fig. 9 is a plan view in larger

size of the manner of clamping the perforators to the connecting-bar; and Fig. 10 is a section in larger size at the line *xx*, Fig. 1.

The vertical shaft C is revolved intermittently, as in said Patent No. 220,312, and projecting from the same are arms e, upon which the signatures are to be laid. The sewing mechanism is not represented in the drawings; but the same is composed of nearly semicircular needles and the looping devices connected with the same, as represented in the aforesaid patents. 55

Each of the arms e is made in the same manner, and I will therefore only describe one of them. The arm e is in the form of a metal bar extending out from the hub of the shaft C and having through it vertical mortises for the passage of the perforators or lances 2. These mortises and lances are at the proper distances apart to perforate the paper at the places where the needles are to enter and to leave the fold of the signature. Each lance or perforator is in the form of a narrow thin blade with a sharp point at one end, and the mortises in the arm e are of the proper size for the perforators 65 2 to slide freely in such mortises, and the arm e is preferably made with removable plates 3, that cover the mortises at one side and retain the lances in their proper positions. 70

The top edge of the arm e is recessed to form 80 the cavities through which the needles pass in performing the sewing, and at the sides of this arm e there are plates 4 of thin sheet metal, the same being secured to the arm by rivets or screws 5. 85

Beneath the arm e and between the plates 4 is a connecting-bar, 6, that is grooved vertically for the reception of the lower ends of the perforators 2, and these are clamped to the said bar 6 by screws 7, so that said perforators 90 are raised and lowered bodily by a movement given to the bar 6. The screws 8 pass through the plates 4, and also through cam-slots 9 in the reciprocating bar 10, and this bar 10 has longitudinal slots 11, that receive the L-shaped 95 lower ends of the plates 12, that hang down from the connecting-bar 6, so that when this bar 10 is moved endwise the cam-slots 9 raise or lower the same, and with it the connecting-bar 6 is moved up and down bodily to project 100

the perforators 2 above the top of the arm *e* or to withdraw the same below such arm.

In the normal position the perforators 2 are depressed, so that the upper ends are entirely below the top edges of the arms *e*, and the signatures are laid upon the arms as said arms come around successively, and when the arm, with the sheet upon it, arrives at the place where the sewing is performed and the shaft 10 and arms are raised up, as in aforesaid Patent No. 220,312, the sheet is held down upon the arm by stationary fingers projecting from the bar that supports the shafts of the needles, and at this moment an end movement is given 15 to the reciprocating bar 10 by any suitable device—such, for instance, as the hook 14, that passes down over the roller or stud upon the reciprocating bar 10—and in so doing the lances or perforators are rapidly raised and 20 pass through the back fold of the signature, making the required perforations for the passage of the sewing-needles, and then, the bar 10 being reciprocated in the other direction, the perforators are withdrawn and the sewing is 25 proceeded with, as in either of the aforesaid patents.

I claim as my invention—

1. The combination, with the mechanism, in

a book-sewing machine, for supporting and moving the parts, of an arm having two parallel plates, a range of perforators, and mechanism for moving the same between and supported by such plates, whereby the folded signature is supported by the upper edge of the arm and hangs thereon while being perforated and sewed, substantially as specified. 30 35

2. The arm *e*, slotted vertically, the perforators received within such slots, the connecting-bar to which the perforators are attached, the plates 4 at the sides of the arm, the reciprocating bar having cam-slots, and the screws passing through the plates 4 and cam-slots, substantially as set forth. 40

3. The combination, with the arm *e* and plates 4, of the perforators passing through 45 mortises in the arms, the connecting-bar 6, to which the perforators are attached, the reciprocating bar 10, and the plates 12, for connecting the bar 6 and reciprocating bar 10, substantially as set forth. 50

Signed by me this 9th day of June, A. D. 1886.

JNO. R. REYNOLDS.
